UNITED STATES PATENT OFFICE.

CHARLES M. MARKHAM, OF MILWAUKEE, WISCONSIN.

COLUMN-CLAMP.

1,270,965.

Specification of Letters Patent.

Patented July 2, 1918.

Application filed October 25, 1915. Serial No. 57,657.

To all whom it may concern:

Be it known that I, CHARLES M. MARKHAM, a citizen of the United States, residing at Milwaukee, in the county of Milwaukee and State of Wisconsin, have invented certain new and useful Improvements in Column-Clamps, of which the following is a specification, reference being had to the accompanying drawing, forming a part thereof.

This invention relates to adjustable metal clamps for binding and holding in place the sections or parts of polygonal columns or forms for molding concrete columns or the like.

Its main objects are to facilitate the construction of such columns and forms; to avoid waste of lumber in the construction of forms for concrete columns or the like; and generally to improve the construction and operation of clamps of this class.

It consists in the construction, arrangement and combination of parts as hereinafter particularly described and pointed out in the claims.

In the accompanying drawing like characters designate the same parts in the several figures.

Figure 1 is a plan view of a column clamp embodying the invention as adjusted and applied to an octagonal column or form which is shown in cross section, parts of the clamp being broken away; Fig. 2 is an outside edge view or elevation of one of the auxiliary bar members of the column; Fig. 3 is a similar view of one of the forked clips for adjustably connecting the auxiliary bar members with the main bar members of the clamp; Fig. 4 is a similar view of the looped or slotted end of one of the main bar members; Fig. 5 is a side view or elevation of the lever or special tool for forcing the main bar members of the clamp into adjusted position on a column or form; Fig. 6 is a view similar to Fig. 1, of a modification of the clamp as adjusted and applied to a square column or form which is shown in cross section, parts of the clamp being broken away; Fig. 7 is an outside edge view or elevation of one of the bar members; and Fig. 8 is a view as seen from the right relative to Fig. 6, of the lever or special tool for a clamp of the modified form.

Referring to Figs. 1 to 5 inclusive, the clamp as shown comprises a number, in the

present case four, main bar members *a*, which are like or similar in construction, each consisting of a straight flat metal bar. Each of the members *a* has a transverse slot *b*, passing through it from side to side adjacent to one end thereof, in which another like or similar bar member is inserted and adjusted lengthwise in assembling the parts of the clamp. This slot may be conveniently formed as shown, by riveting two plates or bars *c* of the same cross section to the opposite faces of the bar *a* at one end and lengthwise thereof, and riveting between the outer ends of the plates or bars *c* a spacing plate or block *d* of the same thickness or cross section, as shown in Fig. 4.

Within and adjacent to the inner end of the slot *b* of each member *a*, a dog *e* is pivoted on a pin or rivet *f*, passing through and secured in the plates or bars *c*. The outer end of the dog is curved eccentrically to its pivot and is toothed or milled so as to engage with the inner edge of an adjoining member *a*, inserted through the slot *b*, and to grip said member tightly between the dog and the outer end of the slot formed by the spacing block or plate *d*, thereby locking the member provided with the dog against outward movement on the other member engaged thereby.

The dogs *e* are formed adjacent to their outer ends and sides with holes *g* to receive a hook or other instrument for pulling them outward to release and disconnect the members of the clamp.

For a square column or form, the clamp has four like or similar members *a*, disposed at right angles to one another, as shown in Fig. 1. For columns and forms of other polygonal shapes, the number and angular arrangement of the members of the clamp may be varied accordingly.

A clamp having four members for a square or rectangular column or form, may be easily adapted for use with an octagonal column or form. To this end the clamp is provided, in addition to the four main members *a*, with four like or similar auxiliary bar members *h*, as shown in Fig. 1. Each of the members *h* is preferably made of a straight flat bar having the same cross section as the main members *a*, and provided at one end with a fork having its crotch disposed obliquely to the sides of the member, for example, at an angle of forty-five de-

grees, for converting a square or rectangular clamp into an octagonal clamp. This fork may be conveniently formed by an angular casting or forging *i*, riveted to one 5 side of the bar member *h*, the adjacent end of which forms a branch of the fork, as shown in Fig. 2. The forks at the ends of the auxiliary members *h* are adapted to embrace the inner sides or edges of the main 10 members *a*, the forks being made of sufficient span or width to receive the three thicknesses of which the looped or slotted ends of the main members are composed. Between their ends the auxiliary members 15 *h* are adjustably fastened to the adjoining main members *a* by forked clips *j*, adapted to fit over and embrace both members and formed with a wedge-shaped crotch *k*, fitting into the angle between the members, the 20 faces of the wedge in a clamp for octagonal columns or forms being at an angle of forty-five degrees to each other. The clips *j*, with the auxiliary members *h*, are secured in place on the main members *a* by set screws *l*, 25 threaded in one of the arms of each clip and adapted to engage with one of the members and to clamp them tightly together.

For tightening or forcing the members of the clamp when they are assembled on a 30 column or form *m*, as shown in Fig. 1, a special tool is provided, as shown in Figs. 1 and 5, consisting of a lever *n*, pivoted by a pin *o* in a lateral forked arm or projection of a grip *p*, which is removably fitted and 35 adjustable on the main bar members *a*. The hole or slot through the grip *p* is inclined or oblique to its sides, as shown in Fig. 1, so that when pressure is applied to the lever *n* to force the members of the clamp into place 40 against a column or form, the grip will cramp or bind and be held against slipping on the member *a* to which it is applied, but when the pressure on the lever is released, the grip can be freely adjusted on the bar member or removed therefrom.

The main bar members *a* are adjusted and tightened in place on the column or form *m* by means of the lever *n*, which is shifted from one member to another, as indicated by dotted lines in Fig. 1. As the slotted end of each of the members *a* is 50 forced by the lever *n* toward and against the column or form *m*, it is locked and held in its adjusted position by the dog *e*, which is 55 turned inwardly into engagement with the adjacent edge of the adjoining member *a*, the dog at the opposite end of said member being also engaged with the member *a* on the opposite side of the column or form, 60 so that the effect is to simultaneously draw or force opposite parallel members of the clamp against opposite sides of the column or form.

The auxiliary members *h*, when used, are 65 adjusted to position on the column or form

by driving or forcing the inclined crotches of the forks *i* and the wedge-shaped crotches *k* of the clips *j* into place on the main members *a*. The auxiliary members *h* are then secured in position by tightening the set 70 screws *l*.

Referring to Figs. 6 and 7, showing a modification of the clamp as applied to a square column or form *m'*, the slots *b'* are shorter than the slots *b* of the first described 75 clamp, and the dogs *e'* instead of being fitted in the slots are removably and adjustably mounted on the bar members *a'* adjacent to the outer sides of slotted ends of the adjoining members through which they pass. The 80 shanks of these dogs are like or similar in construction to grip *p*, which constitutes the fulcrum piece of the lever *n*, and fit loosely and pivot slightly on the bar members *a'*, so that when the dogs are subjected to pressure 85 or strain by engagement with the sides of the adjoining members, they will tightly grip the members on which they are mounted, but when they are relieved of such pressure or strain, their grip will be released and 90 they may be turned slightly and freely, shifted lengthwise of said members, or removed therefrom.

The dogs are formed with lateral offsets *g* at one end for engagement with the outer 95 sides of the slotted ends of the adjoining members *a'*, as shown in Fig. 6.

In other respects this form of the clamp is substantially like the other in construction and operation, and may be provided with 100 auxiliary bar members *h* like or similar to those shown in Fig. 1 for adapting it to columns or forms having a greater number of sides and angles, such as octagonal columns or forms.

With the dogs *e'* constructed and arranged as shown in Fig. 6, a somewhat different tightening lever or tool is used. The lever *n'* is extended beyond its pivot or fulcrum pin *o'* and the lateral arm or projection of the grip *p'* to which it is pivoted or fulcrumed is made longer and spaced farther from the hole or slot in the grip, so that the lever may be reversed in its application to the clamp from the position in which it is 110 shown in Fig. 1, and the shorter arm of the lever will engage with the slotted end of the member *a'* adjacent to the inner side of the member which passes through it and with which the lever is connected.

In adjusting this clamp to a column or form with the lever *n'*, after forcing the slotted end of each member *a'* into place it is locked in adjusted position by crowding the dog *e'* forward tightly against it. The lever 115 is then shifted to another member and so on until all the members are properly adjusted and tightened on the column or form.

Various changes in the details of construction and arrangement of parts may be 120 125 130

made without departure from the principle and scope of the invention as defined in the following claims.

I claim:

5. 1. A column clamp comprising a number of similar and separable bar members, each having adjacent to one end a transverse slot adapted to receive an adjoining member disposed transversely thereto and freely movable lengthwise in working position therein, a locking dog adapted by frictional engagement with each member to hold it against withdrawal lengthwise from an adjoining member, and separate means for forcing the 15 slotted end of each member lengthwise of an adjoining member toward the opposite member.

2. A column clamp comprising a number of similar bar members each having a transverse slot adjacent to one end thereof through which another member is freely adjustable lengthwise in working position, a dog adapted to lock each member in adjusted relation to an adjoining member, a friction grip removably fitted on and adjustable lengthwise of each of the several members, and a lever pivotally connected with said grip and adapted by engagement with the slotted end of an adjacent member to force 25 it into adjusted position on the member passing through it.

3. A column clamp comprising a number of main bar members each having a trans-

verse slot adjacent to one end thereof through which another member is adjustable lengthwise, means for locking the members in adjusted relation to one another, a number of auxiliary bar members each having a fork at one end to embrace the side of a main member obliquely thereto, and forked 40 clips provided with screws for adjustably connecting the auxiliary members at a distance from their forked ends with adjoining main members obliquely thereto.

4. A column clamp comprising a number 45 of main bar members each having a transverse slot adjacent to one end through which another of said members is adjustable lengthwise, dogs for locking said members in adjusted relation to one another, a number of auxiliary bar members each having a fork with an inclined crotch adapted to embrace one side of a main member obliquely thereto, and forked clips with wedge-shaped crotches adapted to embrace and adjustably connect the auxiliary members with the adjoining main members obliquely thereto, the wedge-shaped crotches of the 50 clips fitting into the angles between the main and auxiliary members.

In witness whereof I hereto affix my signature in presence of two witnesses.

CHARLES M. MARKHAM.
